US00D956005S

(12) **United States Design Patent** (10) **Patent No.:** **US D956,005 S**
(45) **Date of Patent:** **** Jun. 28, 2022**

(54) **SHAPED ELECTRODE**

(71) Applicant: **APPLIED Materials, Inc.**, Santa Clara, CA (US)

(72) Inventors: **Robert C. Lindberg**, Rockport, MA (US); **Alexandre Likhanskii**, Malden, MA (US); **Wayne LeBlanc**, Gloucester, MA (US); **Frank Sinclair**, Boston, MA (US); **Svetlana Radovanov**, Brookline, MA (US)

(73) Assignee: **APPLIED Materials, Inc.**, Santa Clara, CA (US)

(**) Term: **15 Years**

(21) Appl. No.: **29/706,320**

(22) Filed: **Sep. 19, 2019**

(51) LOC (13) Cl. **13-03**

(52) U.S. Cl.

USPC **D13/182**

(58) **Field of Classification Search**

USPC D13/113, 117, 121, 122, 118, 182, 183, D13/199; D14/411; D15/144; D8/30; D19/117; D24/133

CPC H01M 10/425; H01F 27/292; H01F 27/2823; H01J 37/3171; H01J 37/05

OTHER PUBLICATIONS

International Search Report and Written Opinion dated Nov. 17, 2020, for the International Patent Application No. PCT/US2020/045232, filed on Aug. 6, 2020, 10 pages.

Primary Examiner — Jennifer O King

(74) Attorney, Agent, or Firm — KDB Firm PLLC

(57) **CLAIM**

The ornamental design for a shaped electrode, as shown and described.

DESCRIPTION

FIG. 1 is an isometric view of our new design; FIG. 2 is a first side view of the design of FIG. 1; FIG. 3 is a second side view of the design of FIG. 1; FIG. 4 is a first end view of the design of FIG. 1; FIG. 5 is a second end view of the design of FIG. 1; FIG. 6 is a top view of the design of FIG. 1; and, FIG. 7 is a bottom view of the design of FIG. 1. The broken lines shown represent portions of the shaped electrode that form no part of the claimed design.

1 Claim, 4 Drawing Sheets
